UNITED STATES PATENT OFFICE.

FREDERICK KOHNLE, OF DAYTON, OHIO, ASSIGNOR TO THE MONARCH MARKING SYSTEM COMPANY, OF DAYTON, OHIO, A CORPORATION OF OHIO.

PRICE TAG.

Application filed July 28, 1921. Serial No. 488,175.

To all whom it may concern:

Be it known that I, FREDERICK KOHNLE, a citizen of the United States, and residing at Dayton, in the county of Montgomery and State of Ohio, have invented a new and useful Improvement in Price Tags (Case B), of which the following specification is a full disclosure.

This invention relates generally to price-tags or tickets for use in price-marking merchandise, and in particular to means for attaching said tags or tickets to the goods.

An object of the invention is to provide means for positively fastening the folder-tag to the goods in such a manner as to insure its continued attachment thereto under the most adverse conditions of handling.

Another object is the provision of a folder-ticket or tag attachable to the goods without mutilation of the same.

Another object is the provision of a double-faced folder-tag or marker, which either entirely surrounds or which overlaps the goods to which it is attached, exhibiting a data-displaying surface at each side of the goods.

Another object is the provision of the folder-tag or folder-ticket provided with fastening means designed to positively and securely hold the tag upon the goods by twice traversing the same.

Another object is the provision of folder-tags or tickets manufactured in strip or gang lengths, the tag widths being defined by consecutively and equally spaced slots or notches extending partially crosswise of the strip, the slots functioning as a means for feeding said strips to printing and cutting position in a machine similar to that described in Letters Patent No. 1,327,241, granted me January 6, 1920.

Other objects and certain advantages will appear in the description of the drawings, forming part of this specification, and reference is made to said drawings, in which:

Fig. 1 is a face view of folder-tags in strip form, the separated tags being designed to be wrapped about the goods.

Fig. 2 is a reverse view of Fig. 1.

Fig. 3 is a face view of one of the tags applied to the goods as a marker.

Fig. 4 is an end view of Fig. 3.

Fig. 5 is an edge view of the detached tag folded for introduction into a tag cutting and printing machine.

Fig. 6 is a face view of a second form of folder-tags in strip form, the separated tags being designed to overlap or straddle the edge of the goods.

Fig. 7 is a separated tag attached as in use.

Fig. 8 is an edge view of Fig. 7.

Fig. 9 is an edge view of folder-tag.

Fig. 10 is a face view of a modified form of folder-tags in strip form, the separated tag being designed to overlap or straddle the goods as in the second form, positive fastening means being carried thereby for attaching the same to the goods.

Fig. 11 is a reverse view of Fig. 10.

Fig. 12 is an edge view from the open edged side of the strip.

Fig. 13 is a central section showing the tag attached to the goods.

Fig. 14 is a detail perspective view of the wire fastening device detached from the tag but showing its elements positioned as they would be when attached thereto.

The numeral 1 designates an elongated paper sheet folded upon itself to form a relatively long and narrow double-ply tag strip providing flaps 2 and 3 of unequal lengths.

Notches or slots 4 are provided along the fold edge of the strip extending inwardly therefrom and part way across the strip and through both plies. One of the flaps, in this instance the longer one, 2, is gummed at its lower edge and on its inner face, as at 5, to form attaching means for each tag of the strip. The tag strip, in its commercial form, is adapted for introduction into a printing or marking and cutting machine, as shown in Fig. 5. In use, the tag is passed around the goods, as shown in Figs. 3 and 4, and the flap 2 is pasted against the outside of the flap 3.

The tag is of simple construction and in virtue of the feed slots therein, can be fed, printed and cut in strip lengths preparatory to use. When applied to the goods, the tag presents a data-receiving surface on each side thereof.

The tags, as an article of commerce, represent a gang tag plural unfoldable layer strip, provided at the longitudinally folded edge with definitely spaced parallel transverse notches from the edge inward and through all the layers, dividing the strip into a plurality of tags and defining the

tag width, the notches providing shoulders adapted to cooperate with the feeding devices of a marking machine.

The tag is adapted to clasp or bind the goods and is secured thereto by an adhesive, as shown in Figs. 1 to 5 inclusive, or metallic fastener as illustrated in Figs. 7, 8, and 10 to 13 inclusive.

A second form of the invention is illustrated in Figs. 6 to 9 inclusive, and comprises a strip folded similarly to the first form, the flaps 20 and 21 being of the same length, and notches 4 being provided along the said fold edge as in the said first form. 10 The folder-tag is placed or clasped over the edge of the goods, (see Fig. 8), and a suitable fastening device, such as a pin, is passed through both plies, flaps or layers and through the goods. A marking surface is 15 thus provided at each side of the goods.

A third form of the folder-tag is shown in Figs. 10 to 14 inclusive and constitutes a modification of the second form in which a wire fastening device is provided and permanently fixed to each tag of the strip at the time of manufacture. A strip is folded upon itself, providing tabs or flaps 30 and 31, the flap 31 being of slightly greater length than its companion. Slots 4, common to all forms 25 of my invention, define the tag width, and a fastening device 35 is provided for each tag midway and adjacent one edge thereof, and at the open side of the strip and tags.

As shown in Fig. 14, a wire is bent upon 30 itself for purposes of reenforcement and for forming a normally projecting portion 37 designed subsequently to twice traverse the goods when the tag is applied thereto. The wire is then bent at a right angle to form a 35 leg 38 lying against the inner surface of the tab 30. The wire then traverses the tab and is again bent, as at 39, the two arms of the wire being then bent away from one another to form the arms 40, the terminals of each 40 arm being passed through the tab and clinched as at 41. A triangular base and anchor is thus formed for securely holding the fastener to the tab 30. The separated tag is attached to the goods in the following 45 manner, (see Fig. 13):

The flaps or tabs 30 and 31 are separated sufficiently to allow the goods to be placed therebetween and the portion 37 of the fastener is made to traverse the goods and a perforation 42 of the flap 31, as said flap is 55 pressed against the goods. The portion 37 is then bent towards the flap 31 and its point inserted through a second opening 43, and thence again through the goods, to be turned 60 around the edge of the flap 30 and pressed against its outer surface. Positive fastening of the tag to the goods is thus accomplished in an efficient and economical manner.

Having described my invention, I claim:

1. A new article of manufacture comprising 65 a tape folded upon itself into a strip of plural non-secured plies, the fold edge extended longitudinally of the tape, said strip at its fold edge having definitely spaced parallel transverse notches, dividing the 70 strip into defined tag widths, the notches providing shoulders adapted to cooperate with feeding devices of a machine for feeding the strip.

2. A new article of manufacture comprising 75 a tape folded upon itself into a strip of plural non-secured plies, the fold edge extended longitudinally of the tape and the plies of unequal length transversely of the 80 strip, said strip at its fold edge having definitely spaced parallel transverse notches dividing the strip into defined tag widths.

3. A new article of manufacture comprising 85 a tape folded upon itself into a strip of plural non-secured plies, the fold edge extended longitudinally of the tape and the plies of unequal length transversely of the strip, said strip at its fold edge having definitely spaced parallel transverse notches dividing the strip into defined tag widths, the 90 longer of said plies having a marginal adhesive coated surface on one side.

In witness whereof, I hereunto subscribe my name, as attested by the two subscribing witnesses.

FREDERICK KOHNLE.

Witnesses:

L. A. BECK,
N. M. SCHMIDT.
